Primary Examiner — Gino Colan*Assistant Examiner* — David Obrien(74) *Attorney, Agent, or Firm* — Bateman IP; Randall B. Bateman(57) **CLAIM**

We claim the ornamental design for a fragrance dispenser, substantially as shown and described.

DESCRIPTION

FIG. 1 is a front perspective view of a fragrance dispenser showing our new design;

FIG. 2 is a rear perspective view thereof;

FIG. 3 is a front view thereof;

FIG. 4 is a right side view thereof;

FIG. 5 is a left side view thereof; and,

FIG. 6 is a top view thereof.
